DESCRIPTION

U.S. PATENT DOCUMENTS

FIG. 1 illustrates a top-front perspective view of the open-top fluid-holding device.

FIG. 2 illustrates a top plan view of the open-top fluid-holding device.

FIG. 3 illustrates a front elevation view of the open-top fluid-holding device.

FIG. 4 illustrates a front cross-section view of the open-top fluid-holding device, taken from the plane and direction of sight indicated by the line 4—4 in FIG. 2; and,

FIG. 5 illustrates a bottom plan view of the open-top fluid-holding device.

This design consists of the visual appearance of an open-top fluid holding device, such as a drinking glass, a shot glass, or a similar fluid holding container. The fluids to be held within the device are not limited to consumable beverages, but may, for example, include antiseptic solutions for cleaning a patient wound and/or a surgical site, during a patent surgery, during which this device would be rested upon a suitable surgical support surface.
